UNITED STATES PATENT OFFICE.

PHILO B. WILLIAMS, OF EDGERTON, OHIO.

CAR-COUPING.

SPECIFICATION forming part of Letters Patent No. 230,379, dated July 20, 1880.

Application filed February 18, 1880.

To all whom it may concern:

Be it known that I, PHILO B. WILLIAMS, of Edgerton, in the county of Williams and State of Ohio, have invented a new and Improved Car-Coupler, of which the following is a specification.

Figure 1 is a sectional plan view of the device on line x x , Fig. 2. Fig. 2 is a sectional side elevation of the same on line y y , Fig. 1.

10 Similar letters of reference indicate corresponding parts.

The invention relates to that class of couplers with which cars can be coupled without the brakeman going between the cars for that purpose; and it consists of a spear or diamond shaped pointed coupling-bar, and of a draw-head provided with an internal shoulder and a swinging metallic plate, which engage and hold the point of the coupling-bar.

20 In the drawings, A A' represent the draw-heads. B is the coupling-bar, provided with a spear or diamond shaped point, a , and with a perforated cross-head, b , at its opposite end.

Within each draw-head is a projecting shoulder, c , and on the opposite side from said shoulder, and nearer the mouth of the said draw-head, is a vertical pin, d , to which pin is secured one end of a broad metallic plate, C, which plate C reaches from top to bottom of 30 draw-head A and extends inward past the shoulder c , and is then bent so that its free end returns toward the mouth of the said draw-head A, and just opposite the shoulder c of the draw-head is an offset, f , made in the said plate C.

Each draw-head is provided with an opening, g , through its top and bottom, for the passage of a coupling-pin, D, which holds the cross-head end of the coupling-bar B, and on 40 the top of each draw-head A A' is a perforated boss or projection, E, down through which is passed the pin F, that holds the metallic plate C against the coupling-bar B when coupling.

h is a rod passing vertically through the 45 draw-head within the bend of the plate C, for the purpose of guiding the entering coupling-bar B.

m is a rod passing through the side of the

draw-head A and fastened to the plate C, by means of which rod m in the plate C may be 50 drawn back to permit the ready withdrawal of the coupling-bar B.

The coupling-bar B, being fixed, as shown, in draw-head A', enters the opposite draw-head until point a of said bar B passes beyond 55 the shoulder c of the draw-head A and the offset f of the plate C, the said head a of the coupling-bar B being directed against the shoulder c of the draw-head by contact with the rod h ; then the pin F is passed down 60 through the boss or projection E, so as to press the offset f of the plate C against the rear slope of the point a of the coupling-bar B, thus holding the said coupling-bar firmly coupled.

65 On withdrawal of the pin F the coupling-bar B is released and the car is uncoupled, and, if necessary, the plate C may be pulled back from the point of the coupling-bar B by the rod m , to more readily release the said coupling-bar.

70 The draw-head A' may be provided with the same devices as the draw-head A, as herein shown and described.

Should one car that is to be coupled be 75 much lower than the opposite one, a portion of the cross-head of the coupling-bar may be cut off—as, for instance, on line z z , Fig. 2—and used as a washer under the other part of the cross-head to raise it to a proper level. 80

Having thus described my invention, I claim as new and desire to secure by Letters Patent—

1. A car-coupler constructed substantially as herein shown and described, consisting of 85 a coupling-bar, B, provided with a diamond or spear shaped point, a , and a perforated cross-head, b , of a draw-head provided with a shoulder, c , and a bent plate, C, that is pivoted on a rod, d , and has an offset, f , and of a 90 guiding-rod, h , as set forth.

2. In a car-coupling, the combination of the pin h with the upward incline of the side of draw-head to guide a diamond-shaped pin-head into position, as described. 95

3. The combination, with draw-head shoul-

der *c*, of the pin *F* and pivoted plate having offset *f* to hold the coupler-pin, as shown and described.

4. The combination of the hook-rod *m* with a pivoted plate, *C*, extending around and under the head of coupler-head, to facilitate the withdrawal of the latter, as specified.

5. In a car-coupler, a draw-head, *A*, having

a shoulder, *c*, provided with bent plate *C*, having an offset, *f*, a guiding-rod, *h*, and a pin, *F*, to construct and arranged substantially as herein shown and described.

PHILO BASLEY WILLIAMS.
